UNITED STATES PATENT OFFICE

WILLIAM BENJAMIN DUNN, OF MOUNT CLEMENS, MICHIGAN

ELECTRICALLY STEAM HEATED RADIATOR

Application filed August 4, 1930. Serial No. 473,043.

This invention relates to portable heaters, and particularly to one embodying an electrically heated steam boiler connected to a steam radiator so as to form an easily portable unit.

An object of the invention is to provide a portable heater which is efficient and simple in operation. Another object is to provide a heater which is, in effect, a complete steam heating system, which may be easily moved about and positioned at the most effective point. Another object is to provide a heater having a steam boiler, the output of steam of which may be easily varied to suit varying temperatures. Other objects may become apparent later.

In the accompanying drawings:

Figure 1 is a side elevation of a steam heater constructed in accordance with this invention.

Figure 2 is an end view thereof.

Figure 3 is a vertical cross-section of the steam boiler shown as a part of Figure 1.

Figure 4 is a cross-section taken on the line 4—4 of Figure 3.

Figure 5 is a cross-section taken on the line 5—5 of Figure 3.

Figure 6 is a cross-section taken on the line 6—6 of Figure 3, this view being partially broken away to show a resistance element.

Figure 7 is an end view of the steam boiler shown in Figure 1, this view being partially broken away to better show the operation of the boiler.

Similar numerals refer to similar parts through the several views. As shown in the drawings this invention is characterized by three main parts, a steam boiler or generator

40 A, a steam radiator B, which may be of the conventional type, and an instrument panel board C, these parts being all inter-connected to form a single unit which is easily portable. Although the radiator B may be of the conventional type, it is preferably of miniature size, so that the heater may be easily carried about.

In detail, the boiler A comprises a hollow metallic casting 10, internally formed with 50 a pair of hollow water tight members 11

which openly communicate with the exterior of the casting and are internally shaped for the reception of disk-shaped resistance units 12. In order to brace these members 11, and also to aid in the conduction of heat from the resistance units 12, bridge members 13 are formed as integral parts of the casting 10. These bridge members serve to brace the hollow members from each other and from the walls of the casting, and also support the upper walls of the casting itself. The uppermost portion of the casting 10 is provided with an outlet 14, one side wall with an outlet 15 and the very bottom-most portion of this wall is provided with a third and smaller outlet 16. The water level in the boiler is preferably kept about on a line with the second outlet 15, as indicated by the dotted line in Figure 1. As a means of ascertaining the water level in the boiler, an opening 17 is provided near the upper part of the casting, and a rod 18 having a buoyant end 19 inserted therethrough so that this end may contact with the water in the boiler. To prevent the escape of steam through this opening 17 a cap 20 may be screwed thereon.

Coupled to the outlet 14 is an upstanding pipe 21, its upper end being bent to form an elbow 22. The panel board C is shaped to extend along the length of the pipe 21 and to cover one side of the boiler A. The panel may be mounted by attachment through a hanger 23 to the pipe 21. Its upper portion is provided with a pressure gage 24 which is coupled through a pipe 25 to the elbow 22 of the pipe 21. A pair of multi-pole electric switches 26 are also mounted to the top of the panel C, one being preferably carried thereby on each side of the pressure gage 24. Current is carried to these switches 26 by a cable 27 which may be connected to any suitable current source, these switches in turn being connected through multi-wire cables 28 to the resistance units 12 which are of the variable resistance type so that the switches 26 may operate to cause these resistance units to generate different amounts of heat.

The top portion of radiator B is coupled

to the bent outlet of the pipe 21 by means of a union 29, and its bottom-most portion to the outlet 15 by means of a similar union. The opposite bottom-most end of this radiator is connected by means of a pipe 30 to the bottom outlet 16 of the casting by a coupling 31. To assure safe operation, the boiler B is preferably supplied with a steam safety pressure outlet 32 of the conventional 10 type.

In operation the boiler A is first filled to the proper level with water, the screw cap 20 being removed so that the indicated rod 18 may be used to ascertain when this level 15 is reached. When the water has been placed in the boiler the screw cap 20 is tightly screwed over the outlet 17 to prevent the escape of any steam. Upon connection of the cable 27 to a current source the switches 20 26 may be operated to energize the resistance elements 12 so as to produce the greatest heat of which they are capable. As soon as the water begins to boil, dry steam will pass through the outlet 14 to the boiler B, while 25 wet steam will pass through the outlet 15 to the boiler. As this steam condenses, and is converted back to water, it will be returned to the boiler A through the pipe 30. The steam gage 24 may be used to enable the operator to properly manipulate the switches 30 26 so as to maintain the desired pressure irrespective of the temperature of the room. If, through in-attention, the switches 26 should be turned so that an excess of steam is 35 generated, the safety valve 32 will function to prevent an explosion.

The heater is easily portable, and very efficient in operation. The boiler A is simply a metallic casting which may be easily and 40 cheaply manufactured, as may the radiator B. Should the electrical resistances 12 be burnt out, they may be easily withdrawn through the open ends of the hollow members 11, whereupon new ones may be re-inserted. 45 Its efficiency is much greater than in the case of heaters employing hot water, the objectionable feature of steam radiators known as "pounding" not being present because of the fact that there are no long pipes for the 50 steam to condense into water, this being the cause of such noise.

It is to be understood that the invention, as here shown and described, is not intended to limit the appended claims thereto, but that 55 these claims are to be construed broadly.

I claim:

1. In a portable steam heater, a steam generator comprising a hollow metallic casting formed interiorly with a plurality of integral 60 hollow watertight members each of which openly communicate with the exterior of the casting and are interiorly shaped to receive disk-shaped electrical resistance units, integral bridging members being formed between 65 each of said members and between said mem-

bers and the walls of said casting, said casting having a plurality of openings one of which is positioned at the top thereof, one at substantially the midpoint of a side wall thereof, one at the bottom thereof and one intermediate of the first two, said last mentioned opening having a buoyant ended rod positioned therein and a steam-tight covering therefor, and disk-shaped electrical heating units for insertion in each of said hollow 75 members.

2. A portable heater including a water container, a plurality of variable capacity electrical resistance units carried by said water container, an upstanding dry steam conduit having its lower end connected to the top of said water container and its upper end bent at a right angle to the rest, a wet steam outlet at substantially the midpoint of one side of said container, a condensed steam conduit connected to the bottom of one side of said container, and a steam radiator, said upstanding conduit having its bent end connected to the top and said coupling and second conduit to opposite ends of the bottom thereof. 80

3. A portable heater including a water container, a plurality of variable electrical resistance units carried by said water container, an upstanding conduit having its lower end connected to the top of said water container and its upper end bent at a right angle to the rest, a coupling connected to substantially the midpoint of one side of said container, a steam radiator, said upstanding conduit having its bent end connected to the top and said coupling and second conduit to opposite sides of the bottom thereof, a panel board carried by said upstanding conduit and extending down along the length thereof and being bent and enlarged so as to cover one side of said container, a pressure gage carried by the upper part of said panel board, a conduit for operatively connecting said gage to the bent part of said pipe, a plurality of multi-pole electrical switches carried by the upper part of 100 said panel board, wires carried back of said panel board for connecting one of said switches to one of said electrical resistance units in each instance, wires for operatively connecting said switches to a current source, 105 and a safety pressure release for said steam radiator. 110
